UNITED STATES PATENT OFFICE.

FORREST JORDAN, OF SAN FRANCISCO, CALIFORNIA.

SHOE-CREEPER.

1,236,572.

Specification of Letters Patent. Patented Aug. 14, 1917.

Application filed November 22, 1916. Serial No. 132,825.

To all whom it may concern:

Be it known that I, FORREST JORDAN, a citizen of the United States, residing in the city and county of San Francisco and State of California, have invented new and useful Improvements in Shoe-Creepers, of which the following is a specification.

This invention relates to a shoe creeper.

One of the objects of the present invention is to provide a skeleton wire sole for shoes which is adapted for use as a protective sole by laborers or as a creeper to prevent slipping when used by hunters or woodsmen.

Another object of the invention is to provide a metallic sole of the character described, which is easily applied or removed, and furthermore provide means for locking the sole against accidental removal when in actual use.

Further objects will hereinafter appear.

The invention consists of the parts and the construction and combination of parts as hereinafter more fully described and claimed, having reference to the accompanying drawings in which—

Figure 1 is a perspective view of the shoe creeper.

Fig. 2 is a bottom view of a shoe sole showing the application of the creeper.

Referring to the drawings in detail, A indicates in general the skeleton frame of the metallic sole, which in this instance consists of a single length of wire, 2, which is bent to form a series of transverse extending connected loops, 3, a sufficient number of loops being provided to permit the entire bottom portion of the sole to be covered as shown in Fig. 2.

For the purpose of securing the metallic sole or creeper to the sole of the shoe indicated at B, a plurality of metallic clips 4, have been provided, a pair of said clips being secured to the forward end of the wire

frame and a second pair to the rear end of the frame. These clips are constructed of any suitable form of metal and each consists of a base section 5, which is provided with loops 6, adapted to embrace and clamp transverse sections on the wire frame, each clip being furthermore provided with an upwardly extending right angular shaped tongue 7, which is adapted to embrace the outer ends of the sole. The several connected transverse loops forming the metallic sole produces sufficient resiliency to per-

mit it to be lengthened or shortened to fit shoes of varying sizes. The forward end of the wire comprising the metallic sole is bent up to form a short pin 8, which is adapted to receive perforated end 9 of a longitudinally extending locking member 10. The rear end of the metallic frame is similarly turned up to form a pin 11, which is adapted to engage in one of a series of perforations 12, formed in the opposite end of the locking member.

The creeper is applied to the shoe sole in the following manner:

The forward clips 4, are first applied to the toe portion of the shoe sole B, as shown in Fig. 2. The rear end of the metallic frame is then pulled rearwardly with the hands until the frame is sufficiently stretched to permit the rear engaging locks 4 to engage the sole of the shoe at the inner part thereof or what is commonly known as the instep. The frame is then released and permitted to contract as much as the width of the sole will permit. The lock bar 10, having previously been applied and engaged with the pin 8 is then swung up into engagement with the pin 11, and if a perfect register with one of the perforations 12 is not immediately obtained it is only necessary to either pull or contract the metallic frame until a register is made. The pin 11, is then inserted and as the metallic frame is always under more or less tension whether expanded or contracted it can readily be seen that a perfect lock is secured which prevents the metallic sole from stretching or becoming accidentally removed from the shoe sole when in natural use, the forward side of the pin 8, and the rear side of the pin 11 being preferably indented or engaged as 13 to prevent locking bar from working off. Any such tendency however, is practically eliminated when the locking bar assumes a position intermediate of the shoe sole and the metallic sole as shown in Fig. 2.

The creeper constructed as herein shown is not only useful as a protecting metallic sole when used by laborers, but has proven to be an efficient creeper to prevent slipping when used by hunters or woodsmen. This construction is so simple and substantial that accidental removal is practically impossible, and as it may be easily applied or removed it can readily be seen that a useful and efficient article has been secured. While metallic clips are here shown as applied it

is obvious that the ends of the loops might be open to form the clips desired, and while the wire is employed it is obvious that any other similar material might be used. The 5 bottom surface of the wire comprising the frame may be roughened as shown in 14, Fig. 2, to prevent lateral slipping of the foot; this roughening being particularly useful in the creeper as employed on ice 10 or rocks made slippery by water action; it may therefore be employed as an efficient ice creeper.

The materials and finish of the several 15 parts of the creeper may be otherwise of such as experience and judgment in manufacture may dictate.

I wish it understood that various changes in form, preparation and minor details of 20 construction may be resorted to within the scope of the appended claims, and I do not 25 wish to limit myself to the specific design and construction here shown.

Having thus described my invention what I claim and desire to secure by Letters Patent is:

1. A shoe creeper comprising a wire frame bent from a single length of wire and adapted to cover the bottom of a shoe sole from the toe to the instep, clips on the wire 30 frame adapted to engage the side edges of the sole, and means for securing the wire frame against longitudinal expansion or contraction.

2. A shoe creeper comprising a frame 35 formed from a single length of wire bent to form a series of transversely extending connected interspaced loops, a plurality of

metal clips secured to said frame adapted to grip the sole of a shoe, and means for securing the wire frame against longitudinal 40 contraction or expansion.

3. A shoe creeper comprising a frame formed from a single length of wire bent to form a series of transversely extending connected interspaced loops and a plurality 45 of metal clips secured to said frame adapted to grip the sole of a shoe, a pin at each end of the frame, and a locking bar engageable with said pins to secure the frame against longitudinal contraction or expansion. 50

4. A shoe creeper comprising a wire frame consisting of a series of transversely extending connected interspaced loops, clips on the frame adapted to grip the sole of a shoe, a pin at each end of the frame and a 55 perforated metal bar engageable with the pins.

5. A shoe creeper comprising a wire frame consisting of a series of transversely extending connected interspaced loops, clips 60 on the frame adapted to grip the sole of a shoe, a pin at each end of the frame and a metal bar having a single perforation at one end and a plurality of perforations at the other end engageable with the pins to secure the frame against longitudinal 65 contraction or expansion.

In testimony whereof I have hereunto set my hand in the presence of two subscribing witnesses.

FORREST JORDAN.
